UNITED STATES PATENT OFFICE.

PERCY D. BREWSTER, OF EAST ORANGE, NEW JERSEY.

COLOR CINEMATOGRAPHY.

Application filed December 28, 1918, Serial No. 268,673. Renewed July 16, 1925.

To all whom it may concern:

Be it known that I, PERCY D. BREWSTER, a citizen of the United States, residing at East Orange, in the county of Essex and 5 State of New Jersey, have invented certain new and useful Improvements in Color Cinematography, of which the following is a full, clear, and exact description.

My present invention relates to the construction of cameras and printers for color cinematography in which the color records are made on separate negative films and printed on opposite sides of a double coated positive and comprises means for securing 15 registry between the images printed on the two sides of the positive film.

My invention consists broadly in perforating the negative films while they are at rest in their film gates and to register the 20 negative films when printing the positive by means of these perforations, and is an improvement over my co-pending application, Ser. No. 224,110 filed March 23, 1918.

I am aware that cameras for black and 25 white have been made in which a single film was perforated in the camera and registered with the positive when printing was secured by those perforations, and that it has been suggested in color photography to 30 expose the separate films and to print by contact on two sides of a double coated positive film from the two negative films obtained, but this process has been a failure to date, due to insuperable difficulties in 35 registration and the object of this invention is to provide means for securing the necessary degree of accuracy in registration.

Registration between the images on the 40 two sides of the positive film should be sufficiently accurate that when the pictures are projected under normal conditions, no separation, fringing or banding of the colors about an object will be noticeable to the ordinary observer.

As the best lenses today have a "circle of confusion" of about one five hundredths of an inch and as the silver grains in the negative film will not record any sharper image, 50 it is apparent that if the error in registry between the two images does not exceed that amount the picture on the screen will be satisfactory.

My invention is illustrated in the accompanying drawings of which Fig. 1 is a horizontal section through the camera; Fig. 2

is a side elevation partly in section; Fig. 3 is a plan of the light splitting surface of the prism; Fig. 4 is an elevation of the perforating plate; Fig. 5 is an enlarged section through the punch plate; Fig. 6 is a plan view of the punch also double size; Figs. 7 to 10 illustrate different arrangements of the punches; Figs. 11 to 16 illustrate various systems of perforations of the 60 film; Fig. 17 illustrates a negative perforated for feeding through the camera; Fig. 18 same film after extra master perforations are cut in camera; Fig. 19 same film after reperforating; Fig. 20 illustrates a 70 specially perforated positive before printing; Fig. 21 same positive after printing and reperforating; Fig. 22 is a diagram of a printer adapted to print one side of the film after the other; Figs. 23 and 24 are 75 plan view and side elevation respectively of a simultaneous printer; Fig. 25 is a plan of the electric controlling commutator; Fig. 26 is a diagram showing the contacts on the commutator; Fig. 27 is a plan of the perforations superposed for printing; Fig. 28 is 80 a side elevation of an optical printer.

Referring to the camera in Fig. 1, the lens 1 is mounted on the front board 2, which is adapted to be moved for focusing 85 on the base 3 between the guides 4, 4 by means of rack 5 and pinion 6 (Fig. 2).

The light rays from the lens 1 enter the splitting prism 7-8 mounted behind the lens and are divided into two color-groups. 90 The surface 9 of prism 7 is adapted to transmit a portion of the light rays reaching it and to reflect a portion. This surface, Fig. 3, may be partly coated with bands of silver and cemented to the adjoining prism 8. 95

The transmitted portion of the light rays pass through the red filter 10 and are recorded on film 11 in the film gate while the reflected light rays pass through the green filter 12 and are recorded on film 13, to produce a red color-value negative image on film 11 and a corresponding green color-value image on film 13. 100

The films 11 and 13, as illustrated, are at right angles to each other, but they may be 105 mounted in any relative position that is in accordance with the angle of the light splitting prisms.

The films may be both panchromatic or one may be specially sensitized for light of the green color group by pinaverdol, for 11 example and the other film sensitized for

the red color group with pinacyanol. In case the films are specially sensitized I sometimes prefer to use in front of the film sensitized for green a yellow filter such as K-2 5 or K-3, which sufficiently reduces the action on the film of the blue or violet light rays. This type of filter is "faster" than the green filters and thereby permits a reduction in time of exposure. This yellow 10 filter is of course not complementary to the red filter.

The two films may be fed through the exposure fields of the camera by any of the well known intermittent feeding mechanisms, such as the Lumière or Geneva movements, the latter being illustrated. The film 11, being fed by means of the sprocket 14, attached to the star wheel 15 and operated by the pin wheel 16 on shaft 17, 15 which also drives the film feeding mechanism of film 13 through the miter gears 18 and shaft 23.

The cams 19 and 20 are mounted on the shafts 17 and 23 respectively, and are arranged to operate the rocker arms 21 and 22.

Film punches 24, 24 are mounted in guides 25, 25 respectively, so as to perforate the films 11 and 13 preferably in the margin. Springs 26, 26 are mounted to act between 30 the guides and the enlarged heads of the punches 24, 24 and tend to force the heads of the punches against the rocker arms and, in turn, to hold the arms against the controlling cam.

35 The cams are preferably so timed that when the film has been fed down one space by the sprockets, the punches cut one or more perforations in each film.

40 The film used in the camera may be without perforations and fed by means of well-known friction feed mechanisms, but I prefer to use film perforated with one or more perforations missing in each series of four, as shown in Fig. 11. I then prefer to arrange 45 the punches so they will cut the "master perforations" 27, 27, Fig. 12, in the space between the feed perforations 28, 28. The film being fed through the camera by means 50 of sprockets on which every fourth tooth is missing.

55 As shown in Fig. 12, these "master perforations" 27, 27 are round, but they may be any shape desired, or made to conform to the present film standard as shown by perforations 29, 29, Fig. 13. It is not essential that these perforations be equally spaced between the feed perforation 28, 28 as indicated in Fig. 12.

60 In case the flattened perforations are used, it is essential that the flat portions of each of the punches 24, 24 should be parallel. I provide means for adjusting the punches by mounting a pin or key 30 arranged to move in a slot 31, in the bushing 32 in the 65 guide 25. The key is fitted without "shake"

in the slot and the whole bushing with the punch may be turned in relation to the guide, being secured by the screws 33, 33 that pass through an enlarged hole in bushing 32 to permit adjustment.

70 The die or aperture plates 34, 34 are attached to guide 25, 25 by means of the screws and dowel pins 35, 35 so that the holes 37, 37 in the die will exactly register with the punches 24, 24 irrespective of any adjustments of the guides. The film is arranged to pass between the die plate 34 and the guide 25, being held against the die plate by means of the pressure plate 38, by the action of the springs 39, 39.

75

80

In my invention I prefer that the punches perforate the films before exposure and remain in place during the exposure and are withdrawn after the exposure and before the films are moved, but the film may be 85 perforated and the punches withdrawn before the exposure or the film may be perforated during or after the exposure, without departing from my invention.

90 One of the punches, or sets of punches, are set arbitrarily to engage the film at the proper point, preferably alongside of the image and this relation to the image is accepted as a standard and the position of the image on the other film in relation to 95 its "master perforations" is adjusted to conform to the relation of the first film as a standard.

99 My invention provides two means by which this registry can be secured; one by 100 moving one image in relation to the other and the second, by adjusting the position of the punches controlling one of the films.

The optical adjustment is secured by mounting the prisms 7-9 on the plate 40, 105 adapted to turn in the base 3 on pin 41, controlled by the action of the capstan screw 42, between stops 43, 43. The clearance holes for the screws 44, 44 in plate 40 are sufficiently large to permit the necessary 110 slight rotation of the plate for adjustment. By adjusting the capstan screw the image on the film 20 is moved in azimuth in relation to the image on the other film. Adjustments in altitude are made by inserting 115 packing or shims under one side of the prism which is held in place by spring clamps 45, 45. Or the plate 40 may be tapped out on either side to receive screws adapted to bear against the prisms and tilt 120 them in either direction desired. Any means of adjustment, single or universal, may be used for controlling the position of the splitting prisms without departing from the spirit of my invention.

125

125 In a well built camera of this type only very small adjustments, possibly a few hundredths of an inch, are necessary to secure registry and I have found by practical experience that shims 46, 46 fitting between 130

the punch guides 25, Fig. 4, and the film gate provide very satisfactory means of securing these adjustments. My practise has been to perforate the two negative films in 5 the camera and to register them by means of pins through the perforations and to measure, under a microscope, the error in registry vertically and horizontally in thousandths of an inch and to alter the 10 thickness of the shims controlling one punch guide to correct the errors thus determined.

I sometimes prefer to use shims 46, 46 between one side and top of the film gate and the guide and to insert the screws 47, 47 15 through the other side of the film gate to force the guide against the shims. By altering the thickness of the shims the error is quickly and accurately corrected. The screws 48, 48 pass through clearance holes in 20 the guides 25, 25 and are tapped in the film gate and may be loosened to permit the necessary adjustments to the guides.

The shutter 49, adapted to protect the 25 films from the action of light when the films are moving is operated by gears 50 and 51 from shaft 23.

Particularly if punches cutting the master perforations in the negative are shaped similarly to the perforations in the positive, 30 I prefer to locate the punches controlling the films exactly similarly spaced in regard to the individual images they control or the perforations are displaced in regard to the location of the image by the exact distance 35 between one or more perforations in the positive as is illustrated by the Figures 7 and 8. In this case one negative would be registered on the positive by means of its master perforation and a perforation suitable for registry purposes in the positive, 40 while the negative film on the other side is registered by its master perforation and a different registry perforation in the positive.

If desired, the two punches Fig. 9 may be 45 set at different levels preferably separated by a multiple of the distance between the perforations in the positive or both punches may be set to perforate in one margin of the film as shown in Fig. 10, or a single hole 50 may be punched in each of the films and by means for contacting against the sides of the film used to secure proper registry without departing from my invention.

Film may be perforated in the camera, 55 as shown in Fig. 14, with master perforations 52, 52 controlling the position of the images and before printing, be reperforated as in Fig. 15, using the master perforations as a guide for the pilot pins in the reperforator and cutting registry perforations 53, 53, which preferably are located at equal distances from the images, or are displaced by a distance the multiple of the distance between perforations in the positive, and which conform to the standard of perforations

used in the positive. I prefer that the three films when printing may be registered by passing properly shaped registry pins through the registry perforations 53, 53 in the two negative films and any registry perforations in the positive. 70

Fig. 16 illustrates a negative film in which the holes 52, 52 perforated in the camera are on different levels as well as the registry perforations 53, 53 cut in the reperforator, 75 but which conform to the standard of perforation in the positive and can be readily registered. The camera perforations 52, 52 may be located between the images near the center of the film and these holes may be 80 used to guide the pilot pins in reperforating.

Film perforated, as shown in Fig. 17, with holes 28, 28, may be used in a camera adapted to advance the film five perforations for 85 every exposure. Every fifth perforation in the margin is omitted and while in the camera a single master perforation 29^a Fig. 18 is cut in the film, preferably near the center while at rest for each exposure 90 and when the film is moved forward for the next exposure a pin, preferably tapered is entered into the perforation to hold it in exact place before the next perforation is 95 cut in the film. Each image is thereby fixed in place by its relation to the perforation above and below it. Before printing or even before development the registry perforations 30, Fig. 19, preferably shaped to conform to the perforation standard of the positive, 100 are cut in the margin by a perforator, their location being controlled by pilot pins entering the perforations 29^a, 29^a above and below the picture. The film may then be registered directly with the positive by pins through its registry master perforation and a registry perforation in the positive. 105

By this method any change in size of the negative, due to shrinkage in developing, 110 fixing and drying the films after exposure, avoided and the negative and positive perforation standards are exactly equal.

Negative film perforated in the camera with round holes or any special shape, as the holes 27, 27 shown in Fig. 12, between successive groups of feed-perforations 28, 28, Fig. 11, may be registered on positive film perforated as shown in Fig. 20 with the specially shaped perforations 28^a, 28^a, 115 between the successive groups of standard perforations 28, 28, and after printing (before development if desired) the positive may be reperforated with the standard perforations cutting away the original registry perforation 28^a. If desired only the holes 28^a, 28^a may be perforated before or during printing and all the standard perforations cut in afterward. If the negative master perforations 27, 27, and the registry perforations 28^a are larger than the stand- 120 125 130

ard perforations 28 provided in the positive for feeding the latter through the projecting machine, the positive perforations 28^a, 28^a may be left as they are instead of being reperforated and the positive film may then be fed through the projector by the remaining perforations 28, 28. In short, it is only when the registry perforations 28^a in the positive are not large enough to receive the feed-claws or teeth of the feed-mechanism of the projecting machine that the registry perforations need to be re-cut.

Using the type of perforation in which the registry master perforation in the negative conform to the positive standards of perforation it is not necessary that the images on both sides of the positive film should be simultaneously printed, but the film may be printed in a type of printer illustrated diagrammatically in Fig. 22. The double coated positive film 84 is fed from roll 85 in contact with the negative film 89 from roll 90 through the printing aperture and registered by pins 93 and printed by light 92, the films being moved intermittently by sprocket 86 and the negative film wound up on spool 91. The positive film 84 continuing along in contact on the other side with the other color record negative 94, fed from roll 95 and printed by light 96 when located in the printing aperture by pins 97, both films being fed intermittently by sprocket 87 and wound up on spools 95 and 88 respectively.

I prefer to print the two sides of the positive simultaneously from the two negatives in the printer illustrated in Figs. 23 to 26 inclusive. The negative 11, the double coated positive film 54 and the other negative film 13 are fed or moved intermittently through the printer by means of the reciprocating feed pins 55 mounted on the cross head 56, the movements of which are controlled by the rod guides 57, 57. The cross head is operated by the rod 58 sliding in the oscillating guide 59, which turns on shaft 60 and is driven by the sliding connecting rod 61 from the crank pin 62, mounted on disk 63 attached to driving shaft 64. Solenoids A, A controlled by the commutator 25, Fig. 19, are adapted to draw in the iron or magnetic portion 66, 66 of the feed pins 55, 55 against the action of springs 67. These feed pins tapered at their tips, are adapted to enter the perforations of all three films and to feed or move them one image space and are adjusted so as to leave the registry perforations of the two negative films and a pair of perforations in the positive films sufficiently superposed to allow the entrance of the suitably tapered registry pins 68, 68 alongside of the exposing aperture 69, open top and bottom in the printer. Suitable lights are arranged above and below the films for exposing the positive film, and shutter mech-

anisms, operating in harmony, with the film feeding mechanism, are provided to protect the film from the action of light when it is moving. The registry pins 68, 68 are operated by solenoids C, C, controlled from the commutator 65, against the action of the springs 70, 70. The films are fed through the printer under light tension when moving or when the registry pins are entering but, just before exposure, the pressure plate, adapted to fit over the films about the aperture plate, and attached to covers in the solenoids D, D, is drawn down firmly against the lower plate of the film gate and the films are forced firmly into contact with each other while printing.

If the negative films are perforated with round holes, 23, 27, Fig. 12, smaller in size than the perforations in the positive or, in fact, if the negative perforations are not similar in shape to the positive perforations, the registry pins, while locating and superposing the two negatives have no control of the position of the images printed on the positive film. Under these conditions each pair of images on the two sides of the positive will register but may not be similarly spaced in relation to the sides of the positive film or the perforations, the result being that the picture will be very unsteady or "weave" when projected on the screen. I overcome this condition in my invention by providing pressure shoes 71, 71 to maintain a varying pressure on the positive film only. These shoes are pressed against the film by means of the flat spreader springs 72, 72. The core 73 in the solenoid B is forced against the spreader spring 72 constantly by flat spring 74, which is adapted to hold the film under the desired tension when being fed, while the solenoid B is adapted to grip the film and hold it firmly after the film has been fed one image space and before the registry pins start to enter and possibly move the positive film by friction from the two negative films being moved slightly in being superposed by the registry pins. I also prefer to provide suitable side guides in contact with the positive to prevent any side displacements of the positive.

The commutator drum 65, operated in synchronism with the film feeding mechanism, is mounted in frame 75 and is adapted to hold the four brushes A, B, C and D against the drum. Metal segments 76, 77, 78 and 79 on the drum properly connected to an electric circuit are adapted to make contacts at the proper times with the brushes A, B, C and D, which are connected to the similarly lettered solenoids. The duration of the contacts with the brushes, and consequently the action of the solenoids is shown by the diagram in Fig. 20. The solenoids A, A are energized while the feeding pins are moving the film, the solenoid B, B are

energized after the film has stopped feeding until nearly ready for the next feeding movement; the solenoids C, C are energized after the film has been gripped by the solenoid B, B and while the exposure has been made and the solenoids D, D are energized after the registering pins have entered the film perforations. Any suitable mechanical movements may be substituted for the solenoids illustrated, without departing from my invention.

If desired all the images can be printed on one side of the positive film in a single light printer and then the positive film turned over and run through the printer again with the other negative film and the images printed on the other side of the film.

Negative film made according to my invention either with round or standard shaped perforation may be printed in the optical printer illustrated in Fig. 28, in which one of the negative films is drawn intermittently down through the film gate 80 and the registry pin 81 used to properly locate the images in the film gate by means of a mechanism similar to that described in the camera. The positive film 82 is fed intermittently up through film gate 83 by suitable means, the position of the images on the positive film being located by the registry pins 84. A suitable source of light is arranged to illuminate the negative film 11, and a shutter arranged to protect the positive film from the action of light when it is in motion. After the series of images on one side of the film are printed from one negative film, the positive film is turned over and again fed through the printer with the other negative film; if the positive is not reversed one of the negative films must be printed through the celluloid.

It is to be understood that, according to my invention, it is immaterial as to the optical system employed for exposing the negative films, whether a single or double lens system be used, whether the two negatives are made simultaneously or consecutively and whether the two films run horizontally or vertically through the camera.

In place of the two separate films, an extra wide film may be used and the negative images exposed side by side, perforations being punched to control the position of the images on the film. After exposure, if desired, these films may be cut apart and used as two separate films or the images on the double width film first on one side of the positive and then on the other.

For three color cinematography three separate films may be used, the position of the images on the three films being controlled by suitable perforations cut in the camera and the films printed in registry by means of these perforations.

I prefer to use on all finished positive

prints the generally accepted standard for perforating so the film may be used in any projector without difficulty, but if I intend perforating the negative with holes that are adapted to register with the positive perforations, I prefer to use in a negative special perforations of standard shape which are larger and spaced farther apart (across the film) than the standard size and separation to compensate for the shrinkage of the negative film in developing and drying. This shrinkage is usually considered to be about one per cent or slightly over, so that the negative perforations are preferably made about one per cent larger and further separated than the positive.

I claim—

1. In the art of color-cinematography, the improvement comprising passing a plurality of negative films step by step through exposure fields, dividing the light rays from the object to be photographed into a plurality of color-groups and projecting the color-groups upon said negative films to form separate series of color-value negative images on the respective films, perforating the films, at definitely located points with respect to the images projected thereon, while the films are at rest for exposure, to produce master perforations, re-perforating the films with said master perforations as guides to produce registry perforations, and printing the several series of color-value negative images on opposite sides of a positive film provided with registry perforations conforming to the registry perforations in the negatives; and in printing, registering registry perforations in one film with registry perforations in another, whereby the images printed on one side of the positive are made to register with those on the other side.

2. In the art of color cinematography, the improvement comprising dividing the light rays from an object to be photographed into color-groups and projecting the same upon separate negative films to produce separate color-value negatives, perforating the negative films at definitely located points relative to the images projected thereupon while the films are in position for exposure to produce master perforations therein, re-perforating the negative films with the master perforations as guides to produce registry perforations, and printing the negative images from one of said negative films upon one side of a perforated positive film and the negative images from another of said negative films upon the other side of the positive film; and in printing, inserting pilot pins into registry perforations in the positive and registry perforations in the negative to produce registry of the images printed on the two sides of the positive.

3. In the art of color cinematography, the improvement comprising passing step-by-

- step through separate exposure fields negative films each having along an edge a series of spaced groups of feed-perforations, dividing the light rays from the object to be
5 photographed into color-groups and projecting the same upon the respective negative films while the latter are at rest to produce thereon separate series of negative images, and while the films are at rest perforating
10 the same between successive groups of feed perforations to produce master perforations at definitely located points relative to the respective images projected thereon; re-perforating the negative films with the master
15 perforations as guides to produce registry perforations; providing a positive film sensi-

tized on both sides, having in an edge a series of spaced groups of feed-perforations and registry perforations between successive groups of feed-perforations, printing the images of one negative film upon one side of the positive and the images of another negative film upon the other side of the positive, and in printing, inserting pilot pins into the registry perforations in 20 at least two films whereby the images printed on one side of the positive are made to register with the respective images on the other side. 25

In testimony whereof I affix my signature.

PERCY D. BREWSTER.

Certificate of Correction.

It is hereby certified that in Letters Patent No. 1,580,115, granted April 13, 1926, upon the application of Percy D. Brewster, of East Orange, New Jersey, for an improvement in "Color Cinematography," errors appear in the printed specification requiring correction as follows: Page 4, line 14, strike out the word "master" and for the word "perforation" read *perforations*; and that the said Letters Patent should be read with these corrections therein that the same may conform to the record of the case in the Patent Office.

Signed and sealed this 11th day of May, A. D. 1926.

[SEAL.]

M. J. MOORE,
Acting Commissioner of Patents.
